UNITED STATES PATENT OFFICE.

JOSEPH W. HORTON, OF BLOOMFIELD, NEW JERSEY, ASSIGNOR TO WESTERN ELECTRIC COMPANY, INCORPORATED, OF NEW YORK, N. Y., A CORPORATION OF NEW YORK.

WAVE-MODULATION SYSTEM.

Application filed December 28, 1923. Serial No. 683,098.

To all whom it may concern:

- Be it known that I, JOSEPH W. HORTON, a citizen of the United States of America, residing at Bloomfield, in the county of 5 Essex and State of New Jersey, have invented certain new and useful Improvements in Wave-Modulation Systems, of which the following is a full, clear, concise, and exact description.
- 10 The present invention relates to modulation of electrical waves for signaling or kindred purposes.
- It is an object of the invention to obtain 15 by modulation certain characteristic wave products to the exclusion of other wave products.
- It has been found that when a continuous 20 wave of given frequency has its amplitude or other characteristic varied in accordance with some time-variation scheme, a large 25 number of wave products, e. g. frequency components, are produced, many if not most of which are both useless and troublesome in any practical installation.
- 25 An object of the invention is to provide a simplified modulating arrangement which is capable of efficiently producing desired 30 modulation products to the exclusion of undesired components.
- 30 A feature comprises a modulator arrangement which is capable of producing desired components without giving rise to certain 35 undesired components, so that there is no need to balance out such undesired components.

40 A further feature of the invention comprises a simplified modulator arrangement for eliminating in an efficient and practical manner a number of undesired components 45 and leaving a single or small number of other components, as desired.

45 The various features and objects of the invention will appear more fully from the following detailed description of typical 50 modulators embodying the invention and illustrated in the accompanying drawing, in which:

55 Fig. 1 is a diagrammatic representation of a modulator employing a vibratory type of magnetic system.

Figs. 2 and 3 are similar representations 60 of modulator systems employing rotating elements; and

Fig. 4 illustrates a modulator capable of

balancing out a large number of components 55 as may be desired.

Briefly and specifically, the invention may 60 comprise a magnetic modulator in which a magnetic circuit is influenced both mechanically and electrically to set up instantaneous field intensities which correspond instant for instant to the amplitude of modulated current or voltage wave to be transmitted. The mechanical variation may be 65 made at the carrier frequency and for this purpose either vibratory elements, such as reeds, tuning forks and the like, may be used, or rotating elements similar to known types of armature may be employed. By so relating the moving mechanical element 70 to the core or field magnets that the reluctances of a plurality of magnetic circuits are varied simultaneously, it becomes a simple matter to associate windings with the field magnets and to connect them in the 75 external circuit in such manner as to make the various components aid or oppose each other in the common outgoing circuit.

Before taking up the detailed description 80 of the figures of the drawing, it may be helpful in pointing out the peculiar advantages of the invention to consider briefly the theoretical principles involved in its operation.

Let it be assumed that the instantaneous 85 reluctance r of a magnetic circuit be representable by

$$r = R (1 + h \cos pt) \quad (1)$$

90 where R is the mean value of the reluctance, h is equal to one half the ratio of the difference between the maximum and minimum reluctance to the average reluctance, and p equals 2π times the frequency 95 of a sustained wave which is to be modulated, which frequency will be called, for convenience, the carrier frequency.

It is also assumed that the magnetic circuit has a polarizing winding through which a 100 polarizing current flows, the instantaneous value I of which is expressible as:

$$I = I_0 (1 + k \cos qt) \quad (2)$$

105 where I_0 is the average current and q equals 2π times the frequency of some variation component, such as a signal frequency, or in the case of speech q may represent a band of

5 frequencies, and k is the usual amplitude coefficient. Instead of employing a neutral core and a steady polarizing current I_0 in the winding, it would, of course, be obvious to employ a permanently polarized magnet and apply only the variation currents to the winding.

10 Under the conditions assumed, a flux ϕ is set up in the magnetic circuit, its value being represented as:

$$\phi = \frac{4\pi n I}{r} = \frac{4\pi n I_0}{R} \frac{(1+k \cos qt)}{(1+h \cos pt)} \quad (3)$$

$$15 = K(1+k \cos qt)(1+h \cos pt + h^2 \cos^2 pt - h^3 \cos^3 pt + \dots) \quad (4)$$

Upon writing $\cos pt$ as

$$20 \frac{1}{2} (e^{ipt} - e^{-ipt})$$

and expanding, it is found that ϕ can be expressed by the series:

$$\phi = A - A_1(p) + A_2(2p) - A_3(3p) + B(q) - B_1(p \pm q) + B_2(2p \pm q) - B_3(3p \pm q) \quad (6)$$

45 This equation may be evaluated for any particular case by referring to the expressions given above for the various coefficients, and it has been thrown into this form merely for convenience in considering the physical significance of the different terms.

50 While equation (6) is in terms of flux variations, it may readily be changed into an expression of the same general form for the voltage variations produced in an outgoing circuit arranged, for example, in inductive relation with the field, by observing the relation:

$$60 e = N \frac{d\phi}{dt} \quad (7)$$

where N is the number of turns in the secondary coil.

Considering now the significance of the various terms of equation (6), the first term 65 A may be passed over as of no importance for modulation purposes, since this term simply represents the steady polarizing current or the magnetization of the core. If a neutral core with no direct current in the windings were used, this term would not be present. Also its magnitude is not in any way affected by the amplitude of the impressed variation currents, such as the signal, since the term k does not appear in the 70 term A . It may be noted, however, that the term A is dependent (as are also the other coefficients of equation (6)) upon the value of h so that any change in structure or adjustment resulting in a new value of h has 75 the effect of changing the value of the coefficients of equation (6).

80 The second term, $A_1 \cos pt$, indicates a sine wave component of flux having a fre-

$$\phi = K(1+k \cos qt)(b_0 - b_1 \cos pt + b_2 \cos 2pt - b_3 \cos 3pt + \dots) \quad (5)$$

85 By equating coefficients, it is found that:

$$b_0 = 1 + \frac{h^2}{2} + \frac{3h^4}{8} + \frac{10h^6}{32} + \frac{35h^8}{128} + \dots$$

$$b_1 = h + \frac{3h^3}{4} + \frac{10h^5}{16} + \frac{35h^7}{64} + \dots$$

$$b_2 = \frac{h^2}{2} + \frac{4h^4}{8} + \frac{15h^6}{32} + \frac{56h^8}{128} + \dots$$

35 and so on, the other b coefficients being in each case expressible in powers of the h coefficients which are odd or even according as the subscript of the respective b coefficient is odd or even.

40 By expanding equation (5) and writing A for Kb_0 , A_1 for Kb_1 , etc., and B for Khb_2 , B_1 for Khb_1 , etc., and also writing (p) for $\cos pt$ etc., we have:

45 frequency equal to the carrier frequency. This term is not a linear function of h since by 85 referring to the expression for b_0 , it will be seen that its equivalent involves the odd powers of h . The other terms in A represent harmonics of the carrier frequency and are also not linear functions of the amplitude of the reluctance variation h .

50 The B terms all contain the first power of h and are, therefore, proportional to the amplitude of the impressed variation component or signal, such as speech for example. A highly important advantage in the system 90 of modulation of the invention is to be seen in the fact that there are no powers of $(\cos q)$ in equation (4) so that in equation 95 (5) there are no terms containing multiples of q . This signifies that there are no harmonics of the signal frequency nor modulation products corresponding to such harmonics.

55 If the signal wave were of the form $k_1 \cos q_1 t + k_2 \cos q_2 t + \dots$, equation (4) shows that there would be no terms containing products of the signal components. This signifies that there will be no 100 intermodulation of components in the signal wave so that, where the signal wave consists of a number of components as in speech, the 105 modulating system of the invention is free from the distortion commonly present in modulator circuits due to interaction in the modulator between the various signal components.

60 The first of the B terms, $B \cos qt$, corresponds to the impressed signal frequency. Since the expression for this term involves b_0 , the amplitude of the output signal is dependent upon the value of h . So long as no 110 adjustments or structural changes are made

resulting in a different value of h , therefore, the modulating system acts like an ordinary transformer for the signal component, the efficiency of which depends upon the reluctance of the core.

The second of the B terms, $B_1 \cos(p \pm q)$, represents the two side bands of the signal on the carrier. The amplitude of these important components is seen to be strictly proportional to the amplitude of the signal, assuming, of course, that the maximum amplitude of the reluctance variation remains constant.

Similarly, the remaining terms indicate side bands of the signal on harmonics of the carrier. Since the term in B_2 and those following involve increasingly higher powers of h , these terms may be made negligibly small in comparison to the primary side bands by making h small.

Aside from the quantitative values above discussed, it will be seen from equation (6) that the character of the output wave may be radically changed by changing the sign of one or both of the independent variables h and k . For example, by providing a plurality of cores and a common means such as a vibrating or rotating member for simultaneously varying the reluctance in a plurality of magnetic circuits, it is possible to cause the reluctance of certain magnetic circuits to be increasing while the reluctance of other magnetic circuits is decreasing in an exactly similar manner. This corresponds to giving h a positive sign (increasing reluctance) in the case of certain of the magnetic circuits and a negative sign (decreasing reluctance) in the case of the other magnetic circuits. By applying the signal windings in reversed sense to the different respective cores, the sign of k may be reversed so that if this sign be called "positive" for one arbitrary direction of connection, it may be called "negative" for the opposite direction of winding. Taking one core (hereinafter designated as No. 0) as a reference core and considering that the direction of the instantaneous signal and reluctance variations (k , h , respectively) are both positive in the case of this core, the effect of changing the sign of h or k or both may be seen from the following table. In this table, the sign of the various output components is given for each of the four cases represented by the four possible combinations of signs of k , h .

Table 1.

Core.	k	h	Output plus terms.	Output minus terms.
0.....	+	+	$A_1, A_2(2p), B_1(q), B_2(2p \pm q)$	$A_1(p), A_2(3p), B_1(p \pm q), B_2(3p \pm q)$
1.....	+	-	All the A terms.....	
2.....	-	+	$A_1, A_2(2p), B_1(p \pm q), B_2(3p \pm q)$	$A_1(p), A_2(3p), B_1(q), B_2(2p \pm q)$
3.....	-	-	All the A terms.....	All the B terms.....

It is apparent that the outgoing circuit may be similarly or oppositely connected to any two or more of the cores. For example, if it be considered that the No. 0 or reference core and core No. 1 are employed and that the outgoing circuit is connected in series aiding as to these two cores, it will be seen that the only components which appear in the outgoing circuit are those in the upper row of the table, grouped under "plus terms," that is, terms in A , $A_2(2p)$, $B(q)$, $B_2(2p \pm q)$, since the terms in the right-hand column opposite the reference core just neutralize the corresponding terms opposite core No. 1, all of which latter terms are positive, as indicated in the table. If the outgoing windings were connected in series opposing, only those terms would appear in the outgoing circuit which are listed in the uppermost row of the table under "minus terms."

If cores No. 0 and No. 2 are employed and if they are connected in series aiding in the outgoing circuit, it is obvious that the outgoing circuit will contain only the terms in A , and if they be connected in series opposing the outgoing circuit will contain only B terms and in each case the terms will be either all of the A terms or all of the B terms respectively. If the No. 0 and No. 3 cores are chosen and if their windings are connected in series aiding, the output circuit will contain the even terms in A and the odd terms in B . If the circuits are oppositely connected, the odd terms in A and the even terms in B will be obtained.

By referring to equation (6), it will be seen that a reversal in the sign of h without changing the sign of k results in reversing the sign of all of the terms of the equation depending upon odd powers of h . Since k appears as the first power in each of the B terms i. e. as an odd power, the effect of changing its sign is to reverse the sign of all of the B terms; whereas if the signs of both k and h be changed, the effect on the B terms will be to reverse the sign of only those terms involving the even powers of h .

The terms of equation (6) thus fall into four classes composed respectively as follows:

I. Terms representing the even-powered multiples of the carrier (including the zero power) without the side-bands, that is, the terms A , $A_2(2p)$, etc.

II. Terms representing the odd multiples of the carrier without the side-bands, that is, the terms $A_1(p)$, $A_2(3p)$, etc.

III. Terms representing the speech side-bands on even multiples of the carrier, and direct speech, that is, the terms B , $B_2(2p \pm q)$, etc.

IV. Terms representing the speech side bands on odd multiples of the carrier, that is, the terms $B_1(p \pm q)$, $B_3(3p \pm q)$, etc.

From what has been said above it follows that the sign of the class I terms is unaffected by the sign of h or k ; the sign of the class II terms depends on the sign of h but is independent of k ; the sign of the class III terms depends on k but is independent of h ; and the sign of the class IV terms depends on both k and h . As has been described above in connection with Table 1, in systems employing two cores, it is possible by controlling the signs of h and k and the connections of the output windings to separate components of two of these classes from components of the other two classes. By employing four cores, however, it is possible to isolate the components of any one class from the others. This will be described more fully in connection with the following description of the drawing.

Referring now to Fig. 1 of the drawing, two cores 10 and 11 are shown arranged to have the length of their air gaps varied by means of the tuning fork 12. These cores are permanently magnetically polarized to provide the requisite biased condition. As explained in the theoretical analysis of the invention above, a polarizing winding and current may be alternatively employed with similar effect. This latter alternative means is illustrated in the circuits of Figs. 2 and 4 to be described. The tuning fork is arranged to be vibrated automatically at some high frequency corresponding to the carrier frequency that is to be used. The prongs of the fork in vibrating approach toward and recede from the pole faces of the respective magnets so that the reluctance of each magnetic circuit is periodically varied at the carrier frequency rate and substantially sinusoidally. Since both prongs approach their respective field magnets simultaneously, the reluctance is decreasing for one core at the same time that it is decreasing for the other core, so that the sign of h is the same for both magnetic circuits.

The cores 10 and 11 are also provided with windings as indicated carrying speech currents derived from the microphone circuit 13. With the reversing switch 14 in the position indicated, it will be assumed that the directions of winding are such that the speech current increases the flux in core 10 at the same time that it decreases the flux in core 11. The two cores therefore correspond to the reference core and to core No. 2 of Table 1. If then the windings in the outgoing circuit 15 are connected in series opposing, the carrier and all its harmonics are balanced out and there is present in the outgoing circuit only the normal speech and the side bands of speech on the carrier and on its harmonics. If the switch 16 were thrown to the other position so as to connect the outgoing windings in series aiding in the circuit 15, the only components trans-

mitted would be the carrier and its harmonics, since the direct speech and all of the side band components would be neutralized.

In the case first assumed above, the windings 17 and 18 are assumed to be connected in series aiding and the carrier frequency is therefore present in the circuit including these windings and the grid and filament of the amplifier tube 19 so that this circuit serves as a control for maintaining the vibrations of the tuning fork 12. The magnet 20 connected in the plate-circuit of the tube 19 serves to drive the tuning fork.

The various combinations obtainable with the circuit of Fig. 1, depending on the positions of the reversing switches 14 and 16, may readily be determined by referring to Table 1.

Types of modulator arrangements employing a rotating element for determining the carrier frequency are shown in Figs. 2, 3 and 4. These arrangements possess greater flexibility than the arrangement shown in Fig. 1, since the number of teeth or poles on the rotating member may readily be varied to change the character of the carrier wave produced and since this type of construction permits a number of cores to be associated readily with the same rotating element.

In the arrangement of Fig. 2, two cores are illustrated, each having a speech input winding connected in the circuit 23, a polarizing winding connected in the circuit of battery 24 and an output winding associated with the outgoing circuit 25. The cores may be permanently magnetically polarized as in the arrangement of Fig. 1, in which case the polarizing windings may be dispensed with. Reversing switches are shown for reversing the connection of one coil of each pair so that the two coils of any pair may be included in each circuit in either an aiding or an opposing sense. In the arrangement of Fig. 2, the two cores are arranged so that similar reluctance changes are produced simultaneously in each of the magnetic circuits. In this respect, therefore, the arrangement of this figure is similar to that of Fig. 1. In the case of Fig. 3, the cores are shown in such position relative to the rotating element 22 that the reluctance of one magnetic circuit is a minimum at the instant when that of the other magnetic circuit is a maximum. It will be understood that windings are to be applied to the cores of Fig. 3 in the same manner as shown in connection with Fig. 2.

In Fig. 4, four cores are arranged to be influenced by the same rotating element 22. Each core is provided with a polarizing winding, a speech input winding and an outgoing winding, as in the case of Fig. 2, and switches are shown for reversing the connection of these various windings to their

respective circuits. As in the similar arrangement of Fig. 2, permanently magnetically polarized cores may be used to obviate the necessity of using polarizing windings and currents.

One of the cores in each of Figs. 2, 3 and 4 is designated "0" on the drawing and will be taken arbitrarily as the reference core. In Fig. 2, the second core bears the designation "3, 4" and in Fig. 3 the other core bears the designation "1, 2, 5 or 6". These designations refer to Tables 2 and 3 which show the various manners of connection to be used for obtaining particular characters of output wave. Similar designations are made of the cores shown in Fig. 4. It will be noted that in each case the core which is designated "3, 4" is positioned with respect to the rotation member 22 in such a way that its reluctance changes are similar from instant to instant to those of the reference core, while the core with the other designation has a reluctance variation 180° different from the reluctance variation of the reference core.

In the following Table 2, the first column indicates a particular one of the cores designated in Figs. 2, 3, or 4. The second and third columns indicate whether the speech and reluctance variations occur in the same sense or in the opposite sense in any core with respect to the reference core. The fourth column indicates whether the output winding of any core and that of the reference core have their connections to the outgoing circuit alike or reversed. The significance of the last four columns is given below in connection with Table 2.

Table 2.

Core.	<i>k</i>	<i>h</i>	Output connections.	I	II	III	IV
1	+	-	Allike	+	-	+	-
2	+	-	Reversed	+	+	+	+
3	-	+	Allike	+	+	-	-
4	-	+	Reversed	-	-	+	+
5	-	-	Allike	+	-	+	+
6	-	-	Reversed	-	+	+	-

In this table, the column I indicates the output components representing the class I terms as defined above in connection with equation (6). The symbols in column I indicate whether in the case of any particular core, with its direction of application of *k* and *h* and with its output connection, all as indicated, these components would tend to aid or oppose the same components obtained with the 0 or reference core.

The column II indicates the output components representing the class II terms as explained above. The column III indicates the class III terms, and the column IV indicates the class IV terms.

By choosing the proper arrangement of two cores with respect to the rotating element and the proper connection between the various coils and their respective circuits in

accordance with the scheme given in Table 2, it is possible to isolate the components of two classes, and by choosing four cores, to isolate the components of any single class. The arrangements that are indicated in Table 2 to be used for isolating any desired components are given in the following Table 3 which is self-explanatory.

Table 3.

To isolate classes.	Use cores.	As in figure.
I and II	0 and 3	2
I and III	0 and 1	3
I and IV	0 and 5	3
II and III	0 and 6	3
II and IV	0 and 2	3
III and IV	0 and 4	2
I	0, 1, 3, and 5	4
II	0, 2, 3, and 6	4
III	0, 1, 4, and 6	4
IV	0, 2, 4, and 5	4

It will be understood that the rotating element 22 may be provided with any desired number of teeth and may be driven in any suitable manner at a speed to produce the desired carrier frequency.

Suitable filtering circuits may be connected in the outgoing circuit 15 or 25, such as a band filter or a low pass or high pass filter for suppressing output components lying in a different frequency range from the components which it is desired to transmit.

The circuits which carry speech currents should have low impedance to speech frequency currents and high impedance to currents of the frequencies not intended to traverse them. Similarly the circuits for the carrier and side-band components should have low impedance for currents of these frequencies and high impedance for speech frequency currents.

The invention is not to be construed as limited to the specific circuit arrangements shown and described but only by the scope of the appended claims.

What is claimed is:

1. The method of modulation comprising varying the magnetomotive force of a magnetic circuit in accordance with a modulating wave, varying the reluctance of the magnetic circuit at the frequency of a wave to be modulated, and utilizing the resultant flux to neutralize certain components and to transmit certain other components of the modulated wave to the outgoing circuit.

2. The method of modulation comprising varying the magnetomotive force of a magnetic circuit in accordance with a signal, mechanically varying the reluctance of the magnetic circuit at a carrier frequency, and utilizing the resultant flux to neutralize certain components and to transmit certain other components of the modulated wave to the outgoing circuit.

3. The method of generating a side band comprising setting up a magnetic field vary-

6
ing in accordance with a range of frequency components, independently and mechanically varying the field strength at a carrier frequency rate, and utilizing the resultant flux to neutralize certain components and to transmit certain other components of the modulated wave to the outgoing circuit.

4. The method of selective wave generation comprising producing simultaneous reluctance variations in a plurality of magnetic circuits, causing the resultant flux variations to set up voltage variations in an outgoing circuit, and utilizing the resultant flux variations of one such magnetic circuit to neutralize in the outgoing circuit certain components set up by the flux variations in the other magnetic circuit.

5. In a modulating system, a magnetic circuit, means to vary the magnetomotive force 20 of said magnetic circuit in accordance with a modulating wave, means to vary the reluctance of said magnetic circuit at the frequency of a wave to be modulated, and means for utilizing the resultant flux to neutralize certain components and to transmit certain other components of the modulated wave to the outgoing circuit.

6. In a modulating system, a plurality of magnetic circuits, means for varying the magnetomotive force of each of said circuits in accordance with a modulating wave, mechanical means for varying the reluctance of said magnetic circuits, and means for utilizing the resultant flux to neutralize certain components and to transmit certain other components of the modulated wave to the outgoing circuit.

7. In a modulating system, a plurality of magnetic circuits each having an air-gap, 40 means to control the flux in each of said magnetic circuits in accordance with a modulating wave, means for varying the air-gap reluctance of said magnetic circuits, and means for utilizing the resultant flux to neutralize certain components and to transmit

certain other components of the modulated wave to the outgoing circuit.

8. In a modulating system, a plurality of magnetic cores each having an air-gap, a winding on each core for controlling the flux 50 in the core in accordance with modulating variations, mechanical means for varying the air-gap reluctance of said cores at the frequency of a wave to be modulated, a second winding on each core, an outgoing circuit, and connections for including said second windings in said outgoing circuit in such a sense as to neutralize in the outgoing circuit certain of the products of modulation.

9. In a modulating system, a plurality of 60 magnetic circuits, windings for influencing each of said magnetic circuits, means to set up signal current variations in said windings, means to produce simultaneous reluctance variations in said magnetic circuits at 65 the frequency of a wave to be modulated, and an outgoing circuit associated in common with said magnetic circuits in a way to have voltage variations set up therein, the sense of the variations in the respective magnetic circuits produced by the signal currents and by the reluctance variations being such that certain modulation components are neutralized in the outgoing circuit and other modulation components are reinforced. 70

10. In a modulating system, a plurality of magnetic cores each having an air-gap, a winding on each core, a microphone circuit connected to all of said windings in common, mechanical means for varying the air-gap reluctance of each of said cores simultaneously at a carrier frequency, a second winding associated with each core, and an outgoing winding connected in common to all of said second windings. 80

In witness whereof, I hereunto subscribe my name this 26 day of December, A. D., 85 1923.

JOSEPH W. HORTON.
